Primary Examiner—Robert C. Spangler

[57] **CLAIM**

The ornamental design for a packaging container for a ribbon cartridge, as shown and described.

DESCRIPTION

FIG. 1 is a perspective view of a packaging container for a ribbon cartridge showing my new design;

FIG. 2 is an exploded perspective view;

FIG. 3 is an exploded view in an unfolded condition; and

FIG. 4 is a view similar to FIG. 2 but showing a modified form of my new design.
